UNITED STATES PATENT OFFICE.

JOHN ARMSTRONG, OF VINE CREEK, KANSAS, ASSIGNOR TO HANNAH ARMSTRONG, OF SAME PLACE.

CORN-SHOCKER.

SPECIFICATION forming part of Letters Patent No. 430,609, dated June 24, 1890.

Application filed January 31, 1890. Serial No. 338,709. (No model.)

To all whom it may concern:

Be it known that I, JOHN ARMSTRONG, of Vine Creek, Ottawa county, Kansas, have invented certain new and useful Improvements 5 in Corn-Shockers, of which the following is a full, clear, and exact description, reference being had to the accompanying drawings, forming a part hereof.

My invention relates to improvements in 10 corn-shockers, its objects being, first, to provide a shocker with which better results can be obtained than by those used heretofore; second, to provide a corn-shocker which is so constructed as to be easily transported over 15 the fields when being used; third, to accomplish these ends with simplicity and economy of construction, which I do by making use of the mechanism and parts illustrated in the accompanying drawings, in which—

20 Figure 1 is the front sectional view of the device, showing it attached to the corn-harvester. Fig. 2 is a side elevation of said shocking device. Fig. 3 is a plan sectional view taken on a line $x-x$ of Fig. 2, and Fig. 25 4 is a perspective view of the receiving and binding device.

Referring to the drawings by letter, A represents my invention constituting two inclined standards or timbers B, which are secured on frame-work C, together with a third 30 upright inclined standard B', which is secured on the frame-work C'.

D is a front cross-beam connecting the beams or timbers C C', and D' is a similar 35 beam connecting the timbers C and C', located a short distance to the rear of the front beam D, said timbers C and C' being provided with bearings c, in which the shaft e works.

40 E represents a roller or pulley secured on shaft e, being provided with an extension E', which has the dovetail members e', which fit in the corresponding notches of said roller E. This projection E' is for the purpose of throwing 45 said pulley or roller out of gear by operating the hand-lever F, which is fulcrumed to the segmental standard g', said hand-lever F having a suitable projection which catches in notches g of the standard G, said standard 50 G being made in the shape of an inverted U and properly secured on the timbers C and D', this shifting device being more clearly illustrated in Fig. 1.

H is a timber secured between the upright inclined beams B B, running from front to 55 rear. On said timber H is secured the platform I, the outer edge of said platform I being provided with a sleeper i, and the inner edge being provided with a corresponding sleeper i', said sleeper i' being beveled, as 60 illustrated in Fig. 1, so that the rollers i'', which are secured on beams of the binding and receiving device K, can be passed thereover. These sleepers i and i' are for the purpose of keeping the receiving device K from 65 rolling off the platform I when said device is being hauled over the ground.

J is a suitable tumbling-joint, which connects the axle of the corn-harvester with the pulley or windlass E of the corn-shocker, said 70 tumbling-joint having the metallic arms j, by which it is secured to the main axle 7 and pulley-shaft e.

K represents the receiving device having the binding or pressing arms k, which are 75 hinged to the horizontal arms k', which in turn are secured between the lugs k'', as illustrated in Fig. 4. The upper ends of the compressing-arms k are provided with eyes, in which are secured suitable ropes a, the outer 80 extremities of said ropes being provided with hooks.

L is a timber, to which lugs k'' are rigidly secured. To each end of said timber L are upright posts l, rigidly secured in position. 85 The upper ends of these posts are provided with eyes l', through which the ropes a may be passed after the device is filled with corn. Said standards or posts l are also provided with loops or staples l'', through which said 90 ropes a may be passed when a small shock is to be made. The vertical binding or compressing arms k are provided near their centers with small eyes, in which are secured the ropes a'. These ropes a' pass through an eye 95 or staple secured in upright standard l, and are for the purpose of releasing the arms k from the shock and lifting the receiver back to its position on the table or platform I. The ropes a are crossed before they are passed 100 through the loops l' or l'' and then passed through the loops opposite their respective compressing-arms.

L' is a sleeper or timber passing centrally under the bottom of the receiving device and 105 properly secured to the front bar l''', on which

the bed-timber L is secured. Passing rearward it is rigidly secured to the frame L'.

Secured at equal intervals between the compressing-arms k and the frame L' are 5 suitable horizontal timbers l''', which receive the corn and hold it on said device. The under surface of the timbers l''' are provided with suitable rollers i'', by which the shock may be rolled from the platform more easily.

10 M is a platform secured on the top of the upright inclined timbers B and B', from which is suspended the cross-tree N by a suitable swinging rod n, which is hung from staple or loop m. Attached to the under 15 side of cross-tree N are the pulleys O, over which pass the ropes or cables o. One end of said ropes o is secured to the roller or pulley E, the other end being provided with rings, in which the hooks which are secured 20 on the ropes a may be secured for raising the receiver from the platform or table I.

P is a suitable cable or rope secured round the roller or pulley E, passing outward, and is passed through the loop or eye b, the lower 25 end of said cable P being provided with a weight p, which serves to reverse the rotation of the roller or pulley E after the shock has been raised by the rope or cable o and let down on the ground, thus slackening the 30 cable o. In order to allow the weight p to operate the roller or pulley E, I throw the said roller out of gear with the part E' by means of hand-lever F, after the shock has been raised by the rope or cable o.

35 Q is a stay-rod, which secures the timbers C and C', it being properly secured by the loop or eyes q. This is clearly shown in Fig. 3.

R represents the corn-harvester to which my device is secured, having endless conveyer 3 mounted on suitable rollers, which 40 conducts the corn from the sickles to the inclined conveyer 4, which elevates and deposits it in the receiver K.

5 represents the reel with which the harvester is provided.

45 6 is a suitable rack secured below the inclined conveyer 4, which receives the corn which is carried up on said conveyers, while the receiver is off of the table I. As soon as 50 the shocker has been replaced on the table the rack is allowed to swing downward, depositing the corn in the receiver.

7 is the axle of the corn-harvester, which is coupled to the windlass-shaft by tumbling- 55 rod joint J, already described. Said shocking device being mounted on suitable caster-wheels 2, having the shocker properly secured to the harvester, and the axle attached to the windlass-shaft by means of said tumbling- 60 joint, the operations are as follows:

The binding and receiving device K is placed on the table I, with the infolding arms k spread open, as illustrated in Figs. 1 and 4, and the team which draws the harvester is 65 started. As the corn is harvested, it is carried to the endless conveyer 3 and elevated

by the inclined conveyer 4 and deposited in the receiving device K. When it has become full, the ropes a are passed through the eyes l' or l'' (according to the size of the shock desired) and the hooks secured in rings with which the ropes or cables o are provided, all slack being taken up by rope or cable P. The windlass E is then thrown in gear by lever F (shown in Fig. 1) and the receiver containing 70 the corn is raised from its position on the platform or table I. The infolding arms are drawn entirely round the corn by having said ropes a passing through the loops l' or l''. As the receiver K swings from the table I, it 75 takes a vertical position, the weight of corn being sufficient to cause it to retain that position until the shock has been deposited on the ground. The hooks are then released from the rings and the arms k withdrawn from 80 the shock by pulling on the ropes a', the pressure of the arms round the corn being sufficient to cause it to retain an upright position after it has been left on the ground. The stay-rod Q must be unhooked before the shock 85 is lowered, so that the device can pass round the shock without throwing it down. As soon as it has passed it is again hooked in position. The receiver K is returned to its position on the table or platform I and is again 90 ready for use.

Having thus fully described my invention, what I claim as new, and desire to secure by Letters Patent, is—

1. A corn-shocker provided with upright 100 timbers, having the horizontal beam H, on which is secured a platform I, which receives the receiving and binding device K, said device K having the infolding arms k, provided with ropes a, which pass through loops or 105 eyes in the opposite upright standard l, for the purposes substantially as set forth and described.

2. A corn-shocker having the receiving device K, provided with the infolding arms k and k', secured in the frame-work L, located at one end of said device, and which receives the corn, the weight of the corn being sufficient to throw it in a vertical position as soon as said device leaves the platform I, which 115 position is retained by the corn after the said device has been released therefrom, the said device being moved from the platform by means of the hook on ropes a, which engage 120 rings attached to one end of cables o, said cables running on pulleys attached to top of the frame, the other end of cables o being secured to the windlass E, which is operated by a tumbling-joint connecting it to the shaft of the 125 corn-harvester, substantially as described.

In testimony whereof I affix my signature in presence of two witnesses.

JOHN ARMSTRONG.
